UNITED STATES PATENT OFFICE.

HARRY H. WILLETS, OF TETREAULTVILLE, QUEBEC, CANADA.

ELECTRIC-LAMP SOCKET.

1,191,641.

Specification of Letters Patent. Patented July 18, 1916.

Application filed December 30, 1912. Serial No. 739,311.

To all whom it may concern:

Be it known that I, HARRY HOWARD WILLETS, a resident of Tetreaultville, district of Montreal, Province of Quebec, Dominion of Canada, subject of the King of Great Britain, have invented certain new and useful Improvements in Electric-Lamp Sockets; and I do hereby declare that the following is a full, clear and exact description thereof.

My invention relates particularly to the socket-shell, and has for its object to simplify the manufacture of the shells of incandescent electric lamp sockets and render the same more durable and less costly; and it may be said briefly to consist of a socket shell consisting of preferably pressed or stamped sheet metal parts having interlocking means.

For full comprehension, however, of my invention, reference must be had to the accompanying drawings forming a part of this specification in which similar reference characters indicate the same parts, and wherein:

Figure 1 is an elevation of a socket provided with a shell constructed according to my invention; Fig. 2 is a view of the parts of the shell separated; Fig. 3 is a transverse sectional view taken on line B B Fig. 1; Fig. 4 is a sectional view taken on line A A, Fig. 1, and drawn to an enlarged scale; and Fig. 5 is a vertical sectional view of the upper portions of the casing members with the slip-ring secured in place.

My improved socket-shell consists of a pair of members *b* and *c* with registering neck portions *b'* *c'* and registering semi-circular notches *b²* *c²* for the stem of the usual key *i*, each integral member with neck being preferably stamped or pressed from sheet metal, preferably brass, the part *b* having lugs *d* and the part *c* slits *e* for receiving the lugs in interlocking engagement. The lugs consist of the extended ends of an exterior circumferential bead *b³* formed near the base of the shell to strengthen it and to accommodate the lugs which are slotted transversely to the bead, the inner edge of the slot being in alignment with the edge of the shell member *b*, the resiliency of the metal causing them to spring into engagement with the slots. This bead construction forms, in effect, a pair of engaging transverse latching bars affording relatively extensive locking faces and securing the

halves of the shell rigidly together. A slip-ring *f* formed of sheet metal bent back upon itself or spun or otherwise manufactured to present inner and outer spaced walls, is fitted upon the neck portions *b'* *c'* when they are brought together, and is held in place preferably by a screw *b⁴* penetrating the ferrule and fastens the socket to the bracket-stem. The portions of the shell are thus rigidly secured together. The usual lining *g* and *h* of vulcanized rubber or other insulating material are inserted into the neck and body of the shell which is fitted with the usual porcelain or fiber contact and key carrying block indicated in dotted lines at *m*, thus completing the socket.

In assembling the socket the contact-carrying block is clasped between the parts *b* and *c* of the shell, the lugs being inserted and sprung into the slits after which the ferrule is secured in place and the socket is ready for use.

In order to provide means for fastening the slip-ring in place when the socket is to be used with a cord for a drop light, for instance, the outer wall of the slip-ring is provided at opposite sides with circumferentially arranged slots 10 and 12 and each half of the neck of the shell has a raised boss 14 adapted to register with and engage the slots when the ring is pressed to place.

What I claim is as follows:

1. An incandescent electric lamp socket shell having as integral component parts a body portion and cap, said shell being divided in a longitudinal axial plane into independent sheet-metal members, and means integral with the said members for locking the same together.

2. An incandescent electric lamp socket shell having as integral component parts a body portion and cap, said shell consisting of a sheet metal member divided longitudinally into two equal parts and means formed integral with the said parts for locking the same together.

3. An incandescent electric lamp socket shell having as integral component parts a body portion and cap, said shell being divided in a longitudinal axial plane into independent sheet-metal members, said members having integral interlocking slits and sprung lugs for engagement with the slits.

4. The combination with an electric lamp socket and an axially split shell for inclosing

- said socket and having a split neck portion; of a split-ring fitted upon the said neck portion for fastening its parts together; an insulating-ring inserted within said split-ring 5 and means passing through said split-ring and insulating-ring for preventing relative displacement of the whole.
5. The combination with an incandescent electric socket shell divided into two members by a plane passing longitudinally through the axis, said shell having a neck portion, the members whereof register with each other and have raised bosses, and a slip-ring consisting of inner and outer walls 10 spaced to be slipped over the said members and having opposite slots for engagement by the bosses on the said members.
6. The combination with an electric lamp socket having a key projecting laterally relatively therefrom; of a shell for inclosing said socket having a neck portion of comparatively small diameter at one end, a circumferential bead in close proximity to the opposite end and an opening for said key, 15 said shell being a sheet-metal member having as integral component parts a body portion and cap and being divided into two parts in a longitudinal axial plane bisecting said opening for the purpose of enabling removal of the shell without disturbing the key; and means for fastening said parts together, said 20 means consisting of a slit in the bead of one part adjacent each side thereof and an integral circumferential extension of the bead of the other part beyond each side edge thereof adapted to enter the slit in the other shell part each extension having a slit there- 25 in to facilitate the interlocking of the parts and to present a flush surface when interlocked.
- 30

- other shell part, each extension having a slit therein to facilitate the interlocking of the parts and to present a flush surface when interlocked.
7. The combination with an electric lamp socket having a key extending laterally relatively therefrom; of a shell for inclosing said socket and having an opening for said key, said shell being divided into two parts in a longitudinal axial plane bisecting said opening for the purpose of enabling the removal of the shell without disturbing the key; and means located at each end of said shell for fastening the parts together.
8. The combination with an electric lamp socket having a key projecting laterally relatively therefrom; of a shell for inclosing said socket and having an opening for the key and a circumferential bead, said shell comprising a sheet-metal member having as integral component parts a body portion and cap and being divided into two parts in a longitudinal axial plane bisecting said opening for the purpose of enabling removal of the shell without disturbing the key; and means for fastening said parts together, said means consisting of a slit in the bead of one part adjacent each side thereof and an integral circumferential extension of the bead of the other part beyond each side edge thereof adapted to enter the slit in the other shell part each extension having a slit there- in to facilitate the interlocking of the parts and to present a flush surface when interlocked.
